UNITED STATES PATENT OFFICE.

WILLARD E. SWIFT, OF WORCESTER, MASSACHUSETTS, ASSIGNOR TO UNITED STATES ENVELOPE COMPANY, OF SPRINGFIELD, MASSACHUSETTS, A CORPORATION OF MAINE.

MACHINE FOR ATTACHING CLOSING-CORDS TO MERCHANDISE-ENVELOPS.

No. 923,602.

Specification of Letters Patent.

Patented June 1, 1909.

Application filed August 7, 1905. Serial No. 272,989.

To all whom it may concern:

Be it known that I, WILLARD E. SWIFT, a citizen of the United States, residing at Worcester, in the county of Worcester and 5 Commonwealth of Massachusetts, have invented a new and useful Improvement in Machines for Attaching Closing-Cords to Merchandise-Envelops, of which the following is a specification, accompanied by drawings forming a part of the same, in which—

Figure 1 represents a side elevation of my improved machine. Fig. 2 represents a merchandise envelop having a closing cord attached thereto. Fig. 3 is a sectional view 15 of the envelop. Fig. 4 represents a side view of the upper portion of the machine, showing the opposite side from that shown in Fig. 1. Fig. 5 is a front view of a portion of the machine. Fig. 6 is a sectional view 20 of the eyelet and cord attaching mechanism. Fig. 7 is a top view of the end of the eyelet conducting tube, and Fig. 8 is a sectional and detached view of the delivery end of the tubular washer guide.

Similar reference letters and figures refer 25 to similar parts in the different views.

My machine is designed to attach the closing string or cord to that class of merchandise envelop in which the seal flap and 30 the body of the envelop are provided with a circular washer or disk attached by eyelets to one of which one end of a closing cord or string is attached, with the free end adapted to be wound successively around 35 the two eyelets and beneath the washers, thereby securely uniting the seal flap and body of the envelop. The washers and eyelets are usually attached to the envelop by an eyeleting machine, and require the attached end of the string or cord to be 40 applied by hand, and it is the object of my present invention to provide a mechanism by which a cord or string of the desired length may be fastened to the envelop automatically during the operation of applying 45 the attaching eyelet and washer, and my invention consists in providing in a single mechanism instrumentalities for applying an eyelet and washers to the envelop, and 50 for feeding to the opening in the envelop

for the eyelet the desired length of string or cord for fastening the envelop, and it further consists in the construction and arrangement of parts whereby this result is accomplished, as hereinafter described and 55 pointed out in the annexed claims.

Referring to the accompanying drawings 1 denotes a portion of the framework of the machine provided with an overhanging arm 2, having vertical ways for a reciprocating 60 plunger 3 to which motion is imparted by a rocking lever 4 mounted in lugs 5 at the top of the arm 2, and operatively connected with the reciprocating plunger by the toggle links 6 and 7 which are connected at their 65 pivoted joint to the fixed framework by a link 8. Motion is given to the rocking lever 4 by a rocking lever 9 carrying on one end a stud 10 which engages a slot 11 in the rocking lever 4. The opposite end of 70 the rocking lever 9 is pivotally connected by a link 12 to a foot treadle 13 which is held in an elevated position by a spring 14 and is depressed by the foot of the attendant at each operation of the machine. The end 75 of the reciprocating plunger 3 carries a hollow spindle 15 inclosing a spiral spring 16 with its tension exerted against the head of a sliding pin 17, causing the pin 17 to normally project beyond the collar 18 which 80 has a screw threaded connection with the hollow spindle 15 and serves to hold the sliding pin 17 in place. The projecting end of the sliding pin 17 is bifurcated by means of a central longitudinal slit 19 forming two 85 elastic prongs 20, 21.

Beneath the sliding pin 17 and in alignment therewith is a fixed pin 22 securely held in the framework of the machine, and provided with a concentric hole 23 nearly 90 its entire length, said hole terminating in an opening 24 in the side of the pin 22. Beneath the fixed pin 22 are a pair of rolls 25 and 26 having corrugated surfaces and adapted by their rotation to feed a cord 27 95 upward through the fixed pin 22 and through the opening 24 in its side. The end of the cord 27 is deflected out of the way of the operative parts of the machine by the depending spring arm 27^a which is at- 100

tached to the fixed arm 2. The feed rolls 25 and 26 are geared together by pinions 28 and 29, and are driven from a ratchet wheel 30 through a train of speed increasing gears 31, so that a slight angular movement of the ratchet wheel will feed at a single operation a sufficient length of string to supply a suitable fastening for the envelop. Motion is intermittently imparted 10 to the ratchet wheel 30 by a pawl 32 carried by one end of a rocking lever 33 operatively connected with the upper rocking lever 4 through a telescopic link, consisting of the two sections 34 and 35 respectively provided with the crossarms 36 and 37, which are united by the spiral springs 38, 38, of sufficient force to hold the telescopic sections 34 and 35 together during the normal operation of rotating the feed rolls 25 and 26, but capable of yielding to an unusual 20 resistance. One of the gear shafts in the train of gears is provided with a cam indicated by the broken lines 39, Fig. 4, having a shoulder 40 adapted to be engaged by the tip 41 of a lever 42, and pivotally connected by one end at 43 to the framework of the machine. The lever 42 is operatively connected by a telescopic link comprising sections 44 and 45, with the upper rocking lever 4, said telescopic sections of the link being held in their normal position by an expansion spring 46. The operation of the pawl 32 and of the lever 42 are so timed that as the pawl 32 has completed its movement in actuating the ratchet wheel 30, the lever 42 will be depressed to bring its tip 41 into the path of and into contact with, the shoulder 40, said tip 41 then acting as a dog to check the further rotation of the feed 30 rolls 25 and 26. Below the opening 24 in the fixed pin 22 is an elastic stripping plate 47, attached at one end to the framework, with its opposite and free end inclosing the fixed pin 22.

45 Pivots supported upon a bracket 48 depending from the arm 2, is an eyelet trough or guide 49, which is filled by hand or otherwise with eyelets 50, the advancing eyelet 51 in the series being stopped by a yielding spring 52, Fig. 7, at the end of the guide and concentrically with the bifurcated sliding pin 17. The eyelet guide 49 is connected by an articulated joint 55 with one arm 56 of a bell crank lever, the other arm 57 having a slot 58 which incloses a stud 59 carried by the reciprocating plunger 3, so that as the plunger moves down, the rocking motion of the bell crank will gradually swing the eyelet guide on its pivotal connection with the bracket away from beneath the pin 17. These parts are so timed, however, that the removal of the eyelet guide does not take place until after the bifurcated pin 17 has entered the eyelet 51, which is thus forcibly ejected from the end of the

eyelet tube by the yielding of the spring 52, leaving the eyelet supported upon the bifurcated end of the pin 17 which is slightly larger than the hole through the eyelet, so that as the pin 17 is forced through the eyelet the prongs 20, 21, are slightly compressed and their elasticity exerts sufficient pressure against the sides of the eyelet to cause it to be held upon the pin. The continued downward movement of the reciprocating plunger 3 carries the eyelet through the opening in the washer 54 and pushes the latter through the opening 53^a in the washer guide 53 until the end of the sliding pin 17 strikes the end of the fixed pin 22, when the sliding pin is forced against the tension of the spiral spring 16 into the hollow spindle 15, and the end of the collar 18 pressing against the eyelet forces it through an opening in the seal flaps *a* of the envelop and through a washer *b*, both of which have been placed by hand on the fixed pin 22 and are supported upon the stripping plate 47. The further downward movement of the collar 18 shears off the string 27 where it projects 90 through the opening 24 and clenches the eyelet, securing one end of the severed piece of string to the envelop. The washer guide 53 is attached to an arm 58^a which is supported upon the lower end of a sliding plate 58^b capable of a slight sliding movement in ways 60 in the framework of the machine and parallel with the reciprocating plunger 3. The reciprocating plunger 3 carries a stud 61 which passes through an elongated opening 62 in the plate 58^b and supports on its outer end an eye plate 63 connected by a spring 64 with a stud 65 held in the plate 58^b. As the reciprocating plunger begins to move down the sliding plate 58^b moves with it until the downward movement of the plate 58^b is checked by means of a screw 66 held in the framework 100 passing through a slot 67 in the plate 58^b. When the downward movement of the plate 58^b has been checked the continued downward movement of the plunger 3 serves to push the washer 54 through the opening 53^a. This limited downward movement of the washer guide 53 is sufficient to bring the 110 washer guide 53 into contact with the spring arm 27^a and deflect it out of the way of the washer 54 and plunger 3 as they descend. The operation of my improved machine is 115 as follows:—With the several parts in the position shown in Figs. 1, 4 and 5 I place a washer *b* on the stripping plate 47, as shown in Fig. 6. Above this I place the seal flap *a* of the envelop, with the end of the fixed pin 22 projecting through an opening in the 120 seal flap of the envelop. Eyelets are supplied to the eyelet guide 49 and washers are supplied to the washer guide 53, causing the eyelet 51 and washer 54 to be held concentrically with the pins 17 and 22, as shown in 125 130

Fig. 6, the washer 54 being held over an opening 53^a in the washer guide and the eyelet 51 being retained in position by the yielding spring 52, Fig. 7. The treadle 13 is then depressed which sets in motion the feed rolls 25 and 26 to feed a piece of string up through the concentric hole in the fixed pin 22 and through the side opening 24, of sufficient length to form a fastening for the envelop. Simultaneously the reciprocating plunger 3 begins to move down causing the eyelet 51 to be engaged by and supported upon the bifurcated end of the sliding pin 17 and carried through the hole in the washer 54 until the end of the pin 17 strikes the end of the fixed pin 22, when it is forced back in to the hollow spindle 15, and the continued downward motion of the collar 18 forces the eyelet through the opening in the seal flap *a* and of the washer 54 and washer *b*, depressing the stripping plate 47 and causing the eyelet to be headed or flanged in the usual and well known manner in eyeleting machines. This downward movement of the eyelet also carries the string through the openings in the seal flap *a* and washer *b* and it is securely held by the flanging of the eyelet. The string is severed between the inside edge of the annular collar 18 and the lower edge of the opening 24. As the foot treadle 13 is released the spring 14 reverses the motion of the operative parts and restores them to their normal position, as shown in Figs. 1, 4 and 5. The operation of the machine causes the two washers *b* and 54 and the eyelet 51 to be securely attached to the envelop, as shown in Fig. 3, and with a severed piece of string 68 projecting beyond the washer 54, with its end firmly secured to the envelop by the upsetting or flanging of the eyelet.

What I claim as my invention and desire to secure by Letters Patent is:—

1. In a machine of the class described, the combination with an eyeleting mechanism, of a fixed pin having a concentric hole in said pin, an opening in the side of the pin communicating with said hole, mechanism for feeding a string through said hole and opening, and means for imparting a periodic and predetermined movement to said feeding mechanism.

2. In a machine of the class described, the combination with an eyeleting mechanism, of a fixed pin having a central hole and a side opening communicating with said hole, a pair of feed rolls below said pin, means for rotating said rolls, whereby a string is fed through said hole and opening.

3. In a machine of the class described, the combination with an eyeleting mechanism of a fixed pin, a longitudinal hole in said pin, a pair of feed rolls below said pin, means for imparting a predetermined rotary movement to said feed rolls, whereby a

string is fed through said hole and means for checking the rotation of said feed rolls.

4. In a machine of the class described, the combination of a fixed pin having a concentric hole and an opening communicating with said hole, means for feeding a string through said hole and opening, and means for severing said string.

5. In a machine of the class described, the combination of a fixed pin having a concentric hole and an opening communicating with said hole, means for feeding a string through said hole and opening between a washer and an envelop, and means for severing the string projecting through said hole, comprising an annular collar and means for sliding said collar over said pin, whereby the string is severed against the edge of said opening.

6. In a machine of the class described, the combination with an eyeleting mechanism, of a fixed pin having a concentric hole for a string, a string feeding mechanism consisting of a pair of feed rolls, means for actuating said eyeleting mechanism, and means for simultaneously rotating said feed rolls.

7. In a machine of the class described, the combination with an eyeleting mechanism, of a fixed pin having a longitudinal hole, and an opening communicating with said hole, a pair of feed rolls for feeding a string through said hole, a pawl and ratchet mechanism for imparting an intermittent motion to said feed rolls, and a locking mechanism for checking the rotation of said feed rolls.

8. In a machine of the class described, the combination with an eyeleting mechanism for applying a washer and an eyelet to an envelop, of means for feeding a string between said washer and said envelop, means for severing the string and means for flanging the eyelet.

9. In a machine of the class described, the combination in an eyeleting mechanism of a fixed pin, a longitudinal hole in said pin, means for feeding a string through said longitudinal hole, means for holding an eyelet concentric with said pin, means for carrying said eyelet into contact with said fixed pin and means for flanging the eyelet.

10. In a machine of the class described, the combination in an eyeleting machine of a fixed hollow pin, means for feeding a string through said hollow pin, means for guiding the string as it issues from said hollow pin, a reciprocating collar for flanging an eyelet over said fixed pin, and means for moving the guiding means for the cord out of the path of said reciprocating collar.

11. In a machine of the class described, the combination of a fixed pin having a longitudinal hole and an opening communicating with said hole, means for feeding a

string through said hole and opening, means for severing the string, an eyelet guide for presenting an eyelet concentric with said pin, a washer guide for presenting 5 a washer concentric with said pin, means for carrying said eyelet and said washer into contact with said pin, a collar for flanging

said eyelet, and means for reciprocating said collar.

Dated this 28th day of July, 1905.
